(57) **CLAIM**

The ornamental design for the clipper, as shown and described in the accompanying figures.

DESCRIPTION

FIG. 1 is a perspective view of a clipper according to the present invention;

FIG. 2 is a top view of the clipper of FIG. 1;

FIG. 3 is a bottom view of the clipper of FIG. 1;

FIG. 4 is a right side view of the clipper of FIG. 1, the opposite side view being symmetric therewith;

FIG. 5 is a front end view of the clipper of FIG. 1; and,

FIG. 6 is a rear end view of the clipper of FIG. 1.

The broken lines showing the blade and cord elements in FIG. 1 are for illustrative purposes only and form no part of the claimed design.
